(57) **CLAIM**

The ornamental design for a module of an electronic personal training device, as shown and described.

DESCRIPTION

FIG. 1 is a perspective view showing the upper surface of the module, including the display panel and user input device. FIG. 2 is a perspective view showing the lower surface of the module.

FIG. 3 is a top view of the module.

FIG. 4 is a bottom view of the module.

FIG. 5 is a front view of the module.

FIG. 6 is a rear view of the module; and,

FIG. 7 is a side view of the module; left and right side views being the same.

The design comprises a module of an electronic personal training device, and which comprises a display panel for providing information to a user while performing activities such as running, swimming, cycling or the like, and a 4-way button or other user input device for receiving commands from the user. The module is insertable into a strap to form a fitness watch, but can also, for example, be inserted into a suitable mount on a bicycle. The module may comprise location determining means, e.g. a global navigation satellite system (GNSS) receiver.
